UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF DELAWARE.

DESIGN FOR A COMBINED RADIATOR AND HOOD FOR MOTOR VEHICLES.

Application filed June 17, 1926. Serial No. 18,076. Term of patent 3½ years.

To all whom it may concern:

Be it known that I, ALFRED F. MASURY, a citizen of the United States, residing in the borough of Manhattan of the city of New York, in the State of New York, have invented a new, original, and ornamental Design for Combined Radiator and Hood for Motor Vehicles, of which the following is a specification, reference being had to the accompanying drawings, forming a part thereof.

The figure is a view in perspective of the design.

I claim:

The ornamental design for a combined radiator and hood for motor vehicles, as shown.

This specification signed this 12th day of June, 1926.

ALFRED F. MASURY.
